UNITED STATES PATENT OFFICE.

HUGO F. LIEDTKE, OF HAGERSTOWN, MARYLAND.

VIBRATOR.

1,346,221.

Specification of Letters Patent.

Patented July 13, 1920.

Application filed November 29, 1919. Serial No. 341,501.

To all whom it may concern:

Be it known that I, HUGO F. LIEDTKE, a citizen of the United States, residing at Hagerstown, in the county of Washington 5 and State of Maryland, have invented certain new and useful Improvements in Vibrators, of which the following is a specification, reference being had therein to the accompanying drawing.

10 This invention relates to fluid-operated vibrators adapted for association with any article, device, machine, or part thereof that it is desired to vibrate or shake to facilitate its action or the performance of a process or operation in which it is used. For example, it is susceptible of being connected with a screen or sieve to aid in the screening or sifting of sand, gravel, or other materials, and it can be associated with a molding-machine or a mold to loosen the pattern 15 from a mold prior to drawing the pattern.

It is an object of the invention to provide a vibrator that is simple in arrangement and efficient and economical of operation, and with this in view the device includes a casing arranged to be secured to the part to be vibrated and inclosing a centrally-journalized unbalanced wheel that is rotated by the impact of fluid, such as air 20 or steam, against buckets, blades, or the like on the periphery thereof.

Another object of the invention is so to form and arrange the parts and details of the device that they may be easily assembled and disassembled.

When read in connection with the description herein, the details of construction and arrangement of parts contemplated by the invention will be apparent from the accompanying drawing, forming part hereof, wherein an embodiment of the invention is disclosed, for purposes of illustration.

While the disclosures herein exemplify what now is considered to be a preferable embodiment of the invention, it is to be understood that it is not the intention to be limited necessarily thereto in interpretation of the claims, as modifications and adaptations within the limits of the claims can be made without departing from the nature and spirit of the invention.

Like reference-characters refer to corresponding parts in the views of the drawing, of which

Figure 1 is a sectional view on the line 1—1, Fig. 2;

Fig. 2 is a sectional view on the line 2—2, Fig. 1, and

Fig. 3 is a side elevation.

Having more particular reference to the drawing, 4 designates a mount or base having bolt-holes 5 for attaching the device to the article or other thing to be vibrated.

An annular casing member 6 is mounted on, and preferably formed integrally with, 65 the base, and it has an extension or enlargement 7 for accommodation of an inlet 8 leading to a constricted nozzle 9 arranged to discharge fluid tangentially into the casing. An exhaust-outlet 10 also is in the annular 70 casing member, and preferably it is aligned with the nozzle.

The annular casing member has on each margin an inclined seat 11 arranged to receive the correspondingly-shaped periphery 75 of a circular plate or cap 12 constituting a side of the casing. Each plate has a centrally-positioned outwardly-extending boss 13, which is shaped laterally to receive a wrench or other turning-tool, and which also 80 affords accommodation for a threaded axially-positioned interior recess 14. The plates 12 are held in position against the marginal seats 11 by a shaft 15, the threaded ends of which are brought to position in 85 the recesses 14 by turning the plates.

A wheel 16 is journalized at its geometrical center on the shaft 15 in the casing, the hub of the wheel being bored with small clearance to fit the shaft and having a recess 17 90 opening to the shaft packed with lubricant. The wheel is unbalanced in any suitable manner, as by an integrally-formed weight 18 at one side of its axis. Radially-extending buckets, blades, or other projections 19 95 on the periphery of the wheel are arranged to move into the line of discharge from the nozzle 9 as the wheel is rotated.

The inlet 8 is screw threaded to take the threaded end of a connection 20 arranged to 100 be received by an end of a hose or other suitable conductor of air or other fluid under pressure.

The relatively few parts of the device may be assembled by placing the wheel on the 105 shaft and then turning the side plates or caps onto the ends of the shaft and against the annular casing member; and disassem-

bly may be effected by reversal of that operation. Accordingly, it is easy to remove, repair, and replace parts or substitute new ones, and to pack the recess 17 with lubricant.

- 5 In use the vibrator is secured to the thing to be vibrated or shaken. For example, when it is desired to vibrate a screen to assist in the screening operation, the vibrator 10 will be attached to any suitable part of the screen, an air-hose in communication with a source of compressed air is fastened to the connection 20, and when air is turned on it will be projected at high velocity against 15 the blades or buckets of the wheel and the wheel rotated at high speed. Since the wheel is unbalanced, due to unequal distribution of weight therein, vibration will be set up and maintained and transmitted to 20 the screen. Rapid vibration in the screen thereby produced will assist in the screening of the material and avoid the necessity of shaking or vibrating the screen either by manual or other mechanical means.
- 25 Having thus described my invention, what I claim as new, and desire to secure by Letters Patent, is—
1. A vibrator comprising a fixed shaft, an unbalanced wheel journaled on said shaft 30 and having peripheral projections, and a nozzle arranged to discharge fluid under pressure against said projections whereby to rotate said wheel.
2. A vibrator comprising a fixed shaft, an unbalanced wheel centrally journaled on said shaft and having peripheral projections, and a nozzle arranged to discharge fluid under pressure against said projections whereby to rotate said wheel.
- 30 3. A vibrator comprising a mount ar-

ranged to be secured to a part to be vibrated, a fixed shaft thereon, an unbalanced wheel journaled on said shaft and having peripheral projections, and a nozzle arranged to discharge fluid under pressure against said 45 projections whereby to rotate said wheel.

4. A vibrator comprising a mount arranged to be secured to a part to be vibrated, a casing member thereon having a fluid-supply inlet and a passage leading therefrom to 50 the interior and an exhaust-outlet, casing sides, a shaft holding said sides against said casing member, and an unbalanced wheel journaled on said shaft and having peripheral projections arranged to have fluid from 55 said passage discharged thereagainst and thereby to be rotated.

5. A vibrator comprising a mount arranged to be secured to a part to be vibrated, an annular casing member thereon formed 60 with marginal seats and a fluid-supply inlet and a passage leading therefrom to the interior and an exhaust-outlet, circular side members having peripheries shaped to rest on said marginal seats, a shaft holding said 65 side members against said seats, and an unbalanced wheel journaled on said shaft and having peripheral projections arranged to have fluid from said passage discharged thereagainst and thereby to be rotated.

6. A vibrator comprising a fixed shaft, an unbalanced wheel journaled on said shaft and having a lubricant-recess opening there- 70 to and having peripheral projections, and a nozzle arranged to discharge fluid under 75 pressure against said projections whereby to rotate said wheel.

In testimony whereof I affix my signature.

HUGO F. LIEDTKE.
